UNITED STATES PATENT OFFICE.

RUDOLPH A. SCHWAHN, OF EAU CLAIRE, WISCONSIN.

HARNESS ATTACHMENT.

1,121,407.

Specification of Letters Patent. Patented Dec. 15, 1914.

Application filed February 26, 1912. Serial No. 679,970.

To all whom it may concern:

Be it known that I, RUDOLPH A. SCHWAHN, a citizen of the United States, residing at Eau Claire, in the county of Eau Claire and State of Wisconsin, have invented new and useful Improvements in Harness Attachments, of which the following is a specification.

My present invention pertains to harness attachments, and contemplates the provision of an attachment adapted to be expeditiously and easily buckled on a split strap of a harness in such manner as to prevent the separated portions of the strap from ripping or tearing farther apart, and also in such manner that it can be used to advantage in the connection of a line guard to a neck strap or a rein-support to a hip strap, or in the connection of any other harness appurtenance to any split strap of a harness.

With the foregoing in mind the invention will be fully understood from the following description and claim when the same are read in connection with the drawings, accompanying and forming part of this specification, in which:

Figure 1 is an elevation showing my novel attachment as carrying a line guard and as buckled or fixed of itself on the neck strap of a harness. Fig. 2 is a detail view, partly in elevation and partly in section, taken at a right angle to Fig. 1. Fig. 3 is a detail view showing the back of the central body portion of the attachment. Fig. 4 is an elevation showing my novel attachment as carrying a rein-support and as buckled or fixed of itself on the hip strap of a harness.

Referring by numerals to the drawings, and more particularly to Figs. 1 to 3 there-
40 of: 1 is a neck strap split or bifurcated at 2, to form sub-straps or tabs 3 in which are apertures 4, and 5 is my novel attachment which may be and preferably is cast of suitable metal and is nickel-plated or otherwise
45 embellished so as to enhance rather than detract from the finished appearance of a harness. The said attachment comprises a central body portion 6 having by preference a square aperture 7, and also having a rear-
50 wardly extending stud 8, Figs. 2 and 3, an upper loop 9, and a lower loop 11. The lower portions of the upper loop 9 extend laterally in opposite directions from the central body portion, and the upper portions of
55 the lower loop 11 similarly extend laterally in opposite directions from the central body

portion, and from this it follows that both loops are of greater width than the body portion. The upper loop 9 is curved rearward or inward so that its upper bar 10 rests in a plane parallel to and inward from the plane of the body 6, and the lower loop 11 is curved rearward or inward so that its lower bar 12 rests in a plane parallel to and inward from the plane of the body 6. By virtue of said construction it will be observed that the attachment is rendered strong and durable; also, that the neck strap 1 can be carried without deflection through the attachment, and the attachment can be slipped on a strap having its lower end split to form sub-straps or tabs, by simply placing the attachment on the strap and adjusting it to the point where it is supported on the strap and the sub-straps or tabs are received in the lower loop 11.

The particular attachment referred to is designed to carry a line guard 14, which line guard is provided with a shank 15, of angular form in cross-section, which shank is disposed in the attachment aperture 7 and is secured in position by upsetting its end against the back or inner side of the attachment. I would here have it understood, however, that the line guard may be fixed with respect to the attachment 5 in any suitable manner without involving departure from the scope of my invention.

One advantage possessed by my novel attachment 5 is the facility with which it can be buckled or secured on a split strap, no sewing whatever being necessary. Another and very important advantage of the attachment is that the lower loop 11 is adapted to effectually prevent the sub-straps or tabs 3 of the strap 1 tearing or ripping apart. In other words, the said lower loop confines the sub-straps or tabs 3 and reinforces the same, and by preventing ripping or tearing apart of the same materially prolongs the usefulness of the strap.

While the attachment shown in Figs. 1 to 3 is designed particularly for effecting connection of a line guard to a neck strap, it is to be understood that my invention broadly stated consists in an attachment applicable to any split strap of a harness and equipped with any kind of harness appurtenance such as a line guard or a rein support or a device for any other purpose.

In Fig. 4, a hip strap 1^a split in the same manner as the neck strap 1 of Figs. 1 and 2,

is shown as carrying an attachment 5^a similar to the attachment 5 and carrying a rein support 14^a.

It will be readily understood from the foregoing that either embodiment of my invention is adapted to be used to advantage in combination with an upper strap, sewed on the upper bar of the upper loop, and lower straps sewed on the lower bar of the lower loop.

Having described my invention, what I claim and desire to secure by Letters-Patent, is:

As a new article of manufacture, a harness attachment consisting essentially of a body flat at its inner side to bear solidly against a strap and having a stud projecting laterally inward from said side to enter an aperture in the strap; a loop, formed integral with and of greater width than the body, curved in a general direction upwardly and inwardly from the body and having outwardly curved end portions and

also having an upper, straight horizontal bar disposed in a vertical plane back of the vertical plane of the body; a second loop, of greater width than the body and integral therewith, curved in a general direction downwardly and inwardly from the body and having outwardly curved end portions and also having a lower curved bar that rests in a vertical plane back of the vertical plane of the body; and an upright rein-support fixedly connected with the center of the body and carried at the outer side of the body and arranged in a vertical plane that extends through the vertical centers of said loops.

In testimony whereof I have hereunto set my hand in presence of two subscribing witnesses.

RUDOLPH A. SCHWAHN.

Witnesses:

W. S. WOODRUFF,
OTTO M. SHRADER.
